BABY CARRIAGE

William Coraccio and James C. Vitullo,
Youngstown, Ohio

Application May 6, 1949, Serial No. 2,499

Term of patent 7 years

(CL. D14—14)

To all whom it may concern:

Be it known that we, William Coraccio and James C. Vitullo, citizens of the United States, residing at Youngstown, in the county of Mahoning and State of Ohio, respectively, have invented a new, original, and ornamental Design for a Baby Carriage, of which the following is a specification, reference being had to the accompanying drawing, forming a part thereof.

Figure 1 is a side view of a baby carriage, showing our new design.

Figure 2 is a front view thereof showing a closure portion of the baby carriage in raised position; and

Figure 3 is a back view thereof and showing a closure portion of the baby carriage in lowered position.

We claim:

The ornamental design for a baby carriage, as shown.

WILLIAM CORACCIO.
JAMES C. VITULLO.
